UNITED STATES PATENT OFFICE.

EDWARD D. SCHMITT, OF BALTIMORE, MARYLAND.

MACHINE FOR PLAITING PAPER.

1,173,610.

Specification of Letters Patent. Patented Feb. 29, 1916.

Application filed February 13, 1914. Serial No. 818,459.

To all whom it may concern:

Be it known that I, EDWARD D. SCHMITT, a citizen of the United States of America, residing at the city of Baltimore, State of Maryland, have invented certain new and useful Improvements in Machines for Plaiting Paper, of which the following is a specification.

This invention relates to a press or equivalent machine for plaiting paper or the like for various uses in the arts, and particularly for use in the manufacture of boxes in accordance with United States Patent No. 1,063,845 dated June 3rd, 1913.

15 The box and the plaited paper referred to as the product of the machine are new articles of manufacture and the machine itself which is constructed for the sole purpose of producing this product, is the first 20 machine ever constructed with this end in view.

The applicant is aware of the existence of various sewing machines having plaiting attachments, but such machines are intended 25 for handling thin fabric while the present machine is in the nature of a press to act on comparatively stiff materials as heavy paper, corrugated paper, fiber board, etc. used in the manufacture of boxes.

30 The function of the machine is to so plait the paper or other materials of which the box is to be made, that the plaits strengthen the box, preferably being so placed as to form the top and bottom edges of the upper 35 right walls whereby the box structure is stiffened to a high degree as explained in the patent referred to. The plaits when formed are preferably secured by means of rivets, staples or similar fastenings or they 40 may be sewed or held in place by the formation of the box or otherwise.

The invention consists in a press having jaws whereby the paper is held and folded to form the plaits, and pressed to close them 45 and render them well defined and permanent, after which they are fastened or held as desired.

The operation consists in feeding the material to the press where it is held between 50 longitudinally extending jaws over the edges of which the material is folded by another jaw member which retires when the fold is formed, the fold or plait being pressed to complete the operation.

55 Where the plaits are to be utilized as

above described to form the top and bottom edges of the box walls, the machine is provided with parallel, longitudinally-extending jaws, the edges of which engage the material on lines spaced apart by a distance 60 equal to the height of the box. The material is folded inward over these jaw edges, the lines of the fold being separated by the height of the box. The paper is then folded outward again on lines which are spaced from the 65 lines of the first folds by a distance equal to the width of the plait. The jaws and folding members are then withdrawn from within the folds or plaits thus formed, and the plaits are pressed flat and fastened if 70 desired.

The machine as shown consists in means for holding the material on lines spaced apart by a distance equal to the height of the box, means for forming a plait of the 75 material and folding it over the holding means, means for pressing the plaits flat, means for feeding the material and means for fastening the plaits.

In order that the invention may be fully 80 understood I have illustrated a preferred form of the machine in the accompanying drawings, of which—

Figure 1 is a rear view. Fig. 2 is a side elevation of the press portion of the machine. Fig. 3 is a central, longitudinal section of the machine on the line 3, 3 of Fig. 1. Fig. 4 is a transverse section on the line 4, 4 of Fig. 3. Fig. 5 is a detail of the presser member. Figs. 6, 7 and 8 are detailed views 85 of the clutch mechanism through which the press is driven. Fig. 9 is a view of the feed dog and operating mechanism. Fig. 10 is a side elevation showing the entire machine. Fig. 11 is a detail view of the longitudinal 90 jaws.

Referring to the drawings by numerals, each of which is used to indicate the same or equivalent parts in the different figures of the drawing, the machine consists of a 100 feeding mechanism 1, a press and plaiting mechanism 2, delivery rolls 3 and plait fastening means 4.

The feed mechanism in the machine shown 105 consists of a feed table 5 slotted longitudinally to receive a primary feed chain 6 having a dog 7 to engage the rear edge of the material which, as will hereinafter be described, is presented in sheets of considerable length. Each sheet may be plaited at 110.

a single operation of the press though they may be otherwise handled. The chain 6 is preferably driven from the press and geared thereto so that the dog 7 moves across the table 5 once for each operation of the press. However, this ratio may be varied and the feed may be otherwise accomplished within the scope of the invention, the operation being performed either by hand or by other mechanism. At the forward end of the table 5 a transverse shaft 7' is journaled. This shaft carries a sprocket 8 for the chain 6 and a sprocket 9 for the secondary feed chain 10, the latter chain which drives the shaft 7' being in turn driven from a sprocket 11 which is driven by suitable gearing from the main shaft 12. The secondary feed chain 10 carries a dog 13 which serves to engage the rear of each sheet of material when delivered by the primary feed and push it forward into operative relation with the plaiting mechanism. The dog 13 serves to move the material but a short distance from where it is disengaged by the dog 7 of the primary feed until it is in exact operative relation with the plaiting mechanism. In order that the operation of the dog 13 may be thus limited in scope, it is movably mounted relatively to the link with which it co-operates, the link being bored to form a sliding bearing for a vertical pin 15 upon which the operative portion or head 16 of the dog is mounted. Below the link the dog is provided with a shoulder or head 17, and a coil spring 18 between the head and the bottom of the link tends to withdraw the dog from operative position. Co-operating with the bottom head 17 is a stationary cam 19 near the rear end of the table. This cam serves to force the dog up into operative position and hold it there for a short portion of the traverse of the chain and then permit it to retire so that the paper is disengaged and secured to the chain 10. At a point on the chain spaced from the dog 13 by a distance equal to one half the length of the chain is a fixed dog 14 as distinguished from the cam actuated dog 13. The chain and plaiting members are so timed that the dog 14 serves to engage the material and move it forward into the bite of the rolls 3 after the plaiting operation.

Referring now particularly to Fig. 4, the plaiting mechanism consists of longitudinal bars or lower jaw members 20 extending the length of the press. These bars while referred to as stationary, have a slight vertical motion, and to this end they are mounted in sockets 22' in brackets 22 secured to the table, see Fig. 11. The jaws 20 are provided at the points where the brackets 22 occur, with depending cups 23 inclosing spiral springs 21. Each spring is placed

under tension by a pin 23' passing downward through the cup and seated in the bracket, the head of the pin serving as a top abutment for the spring, the bearing of which against the bottom of the cup 70 serves to hold the jaw member 20 down. Vertical motion is imparted to the jaws 20 by means of cams 24 on longitudinal shafts 25, one beneath each bar 20, the shafts 25 being oscillated by means of connecting rod and crank 27, see Fig. 3, the latter receiving its oscillatory motion from a crank pin 28 of short radius as compared to crank 27, the pin 28 being carried by the shaft 29 driven by a chain 30 from a sprocket 31 on the main shaft 12, see Fig. 2. The shafts 25 receive their motion immediately from intermeshing bevel gears 32 on these shafts and the transverse shaft 32' to which the crank 27 is secured. As 85 we have previously pointed out, the motion of the shafts 25 is one of oscillation, and in addition to carrying the cams 24 which lift the stationary jaw members 20, they serve to carry the folding members 33 which 90 are in the form of plates mounted on arms 34 secured to the shafts 25. These plates are shown in cross-section in Fig. 4. They extend the full length of and are parallel to the jaw members 20. Co-operating with 95 the lower jaw members 20 are upper jaw members 35. These are bars or plates of the same length as the jaws or bars 20. They are carried by bell crank levers 36 pivoted at 37 on the brackets 38 secured to 100 the carriage 50. The upper arm of each bell crank lever 36 carries a cam follower 39 which engages cams 40 secured to shafts 41 parallel to the jaw members and driven by bevel gears 42, 43, the gears 42 being 105 on the transverse shaft 29 previously described and the intermeshing gears 43 on the longitudinal shafts 41 just referred to, all the levers, arms, cams, etc. carrying and actuating the folding means are repeated at intervals as shown in Figs. 2 and 3.

It will be apparent that the motion of the upper jaw members 35 will be determined by the cams 40 and arms 36 and in a general 115 way would be at right angles to the radius drawn from these plates or jaws to the center of the shafts 37; in other words, it will be a motion inclined slightly upward from the horizontal toward and from the outer 120 edges of the corresponding jaw members 20.

In addition to the cams 40 the shafts 41 carry eccentrics 45 with straps 46 connected to sliding upright members 47 mounted in guideways 48 on the brackets 38. For detail of the sliding members and pressers 49, see Fig. 5. The pressers 49, as we have previously stated, co-operate with the other plaiting members and serve to press the plaits after they have been folded. The 130

plaighting operation is accomplished by up and down motion imparted to the plaighting members by the eccentrics 45.

It will be noted by examination of the drawings, particularly Figs. 1 and 4, that all of the plaighting members are mounted on carriages 50 which in turn engage suitable ways 53 on the table 44 along which they may be moved toward and from each other and toward and from the center of the machine to vary the distance between the plaits. This is accomplished by means of transverse screws 54 engaging threaded apertures in the carriages and mounted to rotate in suitable bearings in the machine frame.

Forward of the plaighting mechanism are the delivery rolls 3. These are constantly driven with a uniform speed of operation by means of a belt 51 on a pulley 52 on the main shaft, the rolls being placed just beyond and out of range of the front end of the material when in plaighting position so that they are not engaged by the material until the plaighting operation is finished and the paper is moved forward into engagement with the rolls.

Referring to Figs. 1, 2 and 10 it will be apparent that the feed chains 6 and 10 are positively and constantly driven from the shaft 12, the drive being from the shaft 12 to the shaft 55 by the sprocket 56 secured to the shaft 12 carrying the chain 57 which engages the sprocket 58 on the shaft 55. The latter shaft is geared to the shaft 59 carrying the sprocket 11 by means of toothed gears 60, 61. The feed chain 10, as previously described, leads over the sprocket 11 and drives the shaft 7' which in turn drives the primary feed chain 6. The feed rolls 3 are also constantly driven from the shaft 12 by way of the belt 51, the pulley 52 which carries the belt being secured to the shaft 12.

The plaighting mechanism, *i. e.*, the jaw and pressing members assembled in Fig. 4 which actually fold and press the material, are intermittently driven, and in the machine of the particular form shown, this drive is accomplished by means of an intermittently engaging clutch 65 shown in detail in Figs. 6, 7 and 8 which transmits intermittent motion to the sleeve 66 on the shaft 12, the sleeve in turn carrying the sprocket 31 which drives the chain 30.

Referring to Figs. 6, 7 and 8, the clutch 65 consists of a radial arm 67 which is formed integral with a hub 68 keyed to the shaft 12. This arm carries a latch 69 secured thereto by means of a pin 70 parallel to the axis of the shaft, the pin being integral with the latch, having an intermediate portion 71 which rides in a radial slot 72 in the arm 67 and having a head 73 in the form of a cam follower which rides in the path 74 in the stationary cam disk 75.

In the form of the invention shown, the

sleeve 66 mounted to rotate on the shaft 12 has a hub 76 notched to receive the latch 69, the notches or teeth 77 being disposed in a direction opposite to that of the revolution of the shaft or having flat radial surfaces 78 disposed in this direction, and the latch having a flat radial surface 79 disposed in the direction of rotation of the shaft. While the surfaces 78 and 79 are described as flat and radial, the essential feature is that the hub has notches disposed in a direction opposite to that of the revolution of the shaft, and the latch 79 has a tooth disposed in the direction of the revolution of the shaft.

It will also be noted as to the cam path 74 that this path might in a general way be divided by a vertical axial plane into two sections, both concentric about the shaft 12 but of different radii. In the machine shown, the portion of lesser radius is at the right and is connected at the top to the portion of greater radius by an incline which joins the circular portion of greater radius near the intersection with the vertical axial plane, and at the bottom the portion of greater radius is joined near the vertical axial plane with the portion of lesser radius by a similar but reverse incline. Starting with the latch in engagement with the notch 77 at the bottom, the arm 67 rotates carrying the sleeve 66 by means of the connection formed by the latch and notch until the follower 73 reaches the upward incline of the path 74 near the upper intersection of the cam surface with the vertical axial plane. When the cam follower rides upward, the latch becomes disengaged from the notch and rotation of the sleeve 66 ceases, the arm 67 rotating free of the sleeve until the downward incline is reached when the latch again comes into engagement with the notch and the sleeve is rotated. Thus the sleeve 66 rotates with the shaft 12 for half of each revolution of that shaft and lies idle for the remainder of each revolution, the plaighting mechanism being correspondingly actuated and permitted to lie idle at intervals of half a revolution of the main shaft. Beyond the delivery rolls 3 in the direction of the feed, is a table 80 which receives the plaited material, and beyond this table and having their centers spaced from the rolls 3 by a distance equal to the length of the sheets of paper to be handled, is a pair of intermittently rotating rolls 81, and beyond these a similarly driven set of rolls 82. Between the rolls 81 and 82 is a head 83 driven by a pulley and belt 84 from any suitable source. This head consists in mechanism adapted to fasten the plaits, and it may be of any preferred type as a stitching, stapling or riveting mechanism, the device indicated herein being in the form of a stapling head described in one or more existing United

Patents. The head 83 is shown in detail in Fig. 130

States patents. It has been indicated in general outline, the exact mechanism being immaterial to this invention.

As has been stated, the rolls 81 operate intermittently and alternatively to the fastening mechanism, so that the material moves forward step by step, being operated upon by the fastening device at each step while stationary. The feed rolls 81 and 82 in the form of the machine shown, are driven from the main shaft 12 of the press by means of an eccentric 85 and rod 86 which serve to rock a lever 87 pivoted at 88 on a bracket the lever 87 being connected at its upper end to a sliding rod 89 carrying pins 90 and 91 which engage the jaws 92 of pawl-carrying levers 93 pivoted at 94 and carrying pawls 95 which engage ratchets 96 which in turn drive the bottom rolls of the co-operating sets 81, 82.

In the operation of the machine, the paper or other material to be plaited, the plain or corrugated paper, fiber-board or the like, cut to the desired length to which the machine is adjusted, is placed on the table 5. As we have pointed out, the feed chains 6 and 10 are constantly driven from the shaft 12 of the press or plaiting machine. The primary feed chain or chains 6 carry each a single dog 7. This dog engages the rear of the material and pushes it forward across the table until it is in a position to be engaged from behind by the retracting dog 13 of the chain 10. The position of this dog during the feeding operation is controlled by the cam 19 as has been previously pointed out, being forced upward against the tension of the spring 18 when it first encounters the cam surface, and held in advance position until the paper is moved into operative position in relation to the plaiting jaws, and in this connection it will also be understood that the operations of the jaws are so timed relatively to the chain 10 that they make but one stroke to a single, complete traverse of the chain, and the operative stroke of the dog 13 terminates just prior to the beginning of the plaiting operation. After the plaiting operation is completed, the dogs 14 come into engagement with the rear edge of the material and advance along the bed of the machine, pushing the material forward into the bite of the delivery rolls 3.

Referring now to Figs. 1 and 4 in which the plaiting mechanism is shown in end elevation and transverse cross-section, respectively, when the paper is fed forward, the followers 39 are on the low portions of the cams 40 so that the upper jaw members 35 are retracted inward and slightly upward in a direction at right angles to the radius drawn from their operative edges to the centers of the corresponding shafts 37. The lower jaw members 20 are also withdrawn

or depressed in response to the action of the springs 21. When the material is disengaged by the retraction of the dog 13, being thereby delivered in operative relation to the jaws, the clutch 65 or more properly the latch 69 thereof, becomes operative and rotates the sprocket 31, driving the chain 30, the shaft 29 and thence the shafts 41, so that the high parts of the cams 40 move into engagement with the rollers 39 and the high parts of the cams 24 move into engagement with the jaws 20, this being substantially the position shown in Fig. 4, that is, the upper jaws 35 swing outward and slightly downward and the lower jaws 20 move upward to a slight degree. Thus the material is gripped on two parallel longitudinal lines which may extend the length of the material and which are preferably spaced apart by a distance equal to the width of the upright walls of the box to be made, though the jaws may be otherwise arranged and the plait otherwise disposed within the scope of the invention. Incidentally from the arrangement of the jaws and the particular motion given to the upper jaws, the material is extended and held in flat condition as to its central zone between the outer edges of the jaw members.

The means for operating the folding members 33 has already been described as identical with that moving the cams 24 and consisting of cranks 27 and 28 operating the shaft 25, imparting to this shaft and to the jaws 33 an oscillatory motion which from the arrangement of these cranks, as shown in Fig. 3, it will be understood is of a harmonic nature, so that the folding members 33 have been moving upward slowly during the operation described. They now swing upward about the jaw members 20 and 35 well over and past the latter members, carrying the paper with them and folding it about the outer edges of the jaws 35. The fold thus formed is a double or Z fold, the outer edges of the material being held from swinging freely upward by the presser members or presser feet 49, but the presser feet 49 are themselves given a vertical harmonic motion from the eccentrics 45. During the operation described, these presser feet have been in the upper dwell, but now the folding members 33 and the upper jaws 35 having accomplished their function which is that of holding the material and entering and defining the creases of the Z fold, they are withdrawn, the followers 39 encountering the drop of the cams 40 and the cranks 27 swinging back on the return stroke so the jaws 35 are withdrawn. As soon as the members 33 and 35 start to retire, the presser feet 49 descend and when the members 33 and 35 are out of their path, they press the Z fold, or more particularly, the outer edges of the Z folds flat. Next the presser feet 130

are withdrawn upward and the lower jaws 20 are released and drawn downward by their springs, the cams 24 passing out from under the longitudinal bars which form the 5 lower jaw members. When the plaited paper is thus released, the dog 14 on the chain 10 which travels continuously, comes in contact with the rear edge of the sheet and pushes it forward into the bite of the 10 delivery rolls 3 by means of which it is pressed forward on to the table 80 and presented to the bite of the intermittently rotating rolls 81. By means of these rolls it is presented to the action of the stitching or 15 stapling head 83 through which it passes to the second set of intermittently rotating rolls 82 by which it is delivered in plaited condition ready to be folded to form the box or other finished product.

20 I have thus described specifically and in detail a machine by which the operation of plaiting paper either corrugated or plain, or other similar material for use in the manufacture of boxes in accordance with my 25 Patent No. 1,063,845, or otherwise, may be accomplished, and I desire to have it understood that the type of box referred to is a new one, that the plaited paper which is the product is likewise new, and this is the first 30 machine which has ever been produced to accomplish this operation. Therefore the specific details while they are necessary to a full comprehension of the operation, are not in themselves essential in the particular 35 form in which they are disclosed, but on the other hand, these details may be widely varied and wholly different elements having similar or equivalent functions may be substituted therefor within the scope of my invention.

40 What I claim and desire to secure by Letters Patent is:

1. In a machine for manufacturing plaited box blanks of heavy paper board or 45 the like the plaits serving as reinforcing means at the top and bottom edges of the box, means for holding the material, means for bending the paper to form two parallel plaits having their outer edges spaced apart 50 by a distance equal to half the box and means for pressing the plaits to make them permanent and form them into reinforcing members at the top and bottom edges of the box.

55 2. In a machine for manufacturing plaited box blanks of heavy paper board or the like, the plaits serving as reinforcing means at the top and bottom edges of the box, means for holding the material along 60 two parallel lines, said means being spaced by a distance corresponding to the height of the box, means for bending the paper to form two parallel plaits having their outer edges spaced apart by a distance equal to 65 the height of the box, and means for press-

ing the plaits to make them permanent and form them into reinforcing members at the top and bottom edges of the box.

3. In a machine for manufacturing plaited box blanks of heavy paper board or 70 the like, the plaits serving as reinforcing means at the top and bottom edges of the box, means for holding the material along two parallel lines, said means being spaced by a distance corresponding to the height 75 of the box, means for bending the paper to form two parallel plaits having their outer edges spaced apart by a distance equal to the height of the box, means for pressing the plaits and means for fastening them to 80 make them permanent and form them into reinforcing members at the top and bottom edges of the box.

4. In a machine for plaiting paper or the like, means for gripping the material, means 85 for folding the paper about the gripping means, means for forming a second fold about said second mentioned means thus forming a Z fold and pressing the Z fold thus formed flat. 90

5. In a machine for plaiting paper, means for gripping the paper on two parallel lines, means for folding the paper inward about both said means, means for bending the paper about said folding means, and pressing 95 both said folds.

6. In a machine for plaiting paper in the manufacture of paper boxes, two sets of parallel outwardly disposed jaw members for gripping the paper on parallel lines, 100 folding members swinging about said jaw members, pressing means and means for actuating the said members and moving the folding members and one of each set of jaws out of the path of the pressing means, and 105 means for forcing said pressing members downward on to the folded material to press the folds.

7. In a machine for plaiting paper in the manufacture of paper boxes, two sets of 110 parallel outwardly disposed jaw members for gripping the paper on parallel lines, the outer edges of said jaw members being spaced apart by a distance equal to the height of the box to be manufactured, folding members swinging about said jaw members, pressing means and means for actuating the said members and moving the folding members and one of each set of jaws out of the path of the pressing means, and means 115 for forcing said pressing members downward on to the folded material to press the folds.

8. In a machine for plaiting paper in the manufacture of paper boxes, parallel jaw 125 members, cooperating jaw members mounted to swing, and means for swinging them outward toward and inward from the edges of said first mentioned jaw members, folding members parallel to said jaw members, 130

and means for swinging them about the outer edges of the jaw members and pressing means adapted to move toward and from said first mentioned jaw members, 5 the swinging jaw members being timed to swing inward and the folding members being timed to swing outward and downward out of the path of said pressing means as they move toward the first mentioned jaw members.

9. In a machine for plaiting paper in the manufacture of paper boxes, parallel jaw members, means for moving said jaw members vertically, coöperating jaw members mounted to swing and means for swinging them outward toward and inward from the edges of said first mentioned jaw members, folding members parallel to said jaw members, and means for swinging them 15 about the outer edges of the jaw members and pressing means adapted to move toward and from said first mentioned jaw members, the swinging jaw members being timed to swing inward and the folding members being timed to swing outward and downward out of the path of said pressing means as they move toward the first mentioned jaw members.

10. In a machine for plaiting paper in the manufacture of paper boxes, parallel jaw members, means for moving said jaw members vertically, coöperating jaw members mounted to swing and means for swinging them outward toward and inward from the edges of said first mentioned jaw members, folding members parallel to said jaw members, and means for swinging them 20 about the outer edges of the jaw members and pressing means adapted to move toward and from said first mentioned jaw members, the swinging jaw members being timed to swing inward and the folding members being timed to swing outward and downward out of the path of said pressing means as they move toward the first mentioned jaw members.

11. In a machine for plaiting paper in the manufacture of paper boxes, parallel jaw members, means for moving said jaw members vertically, coöperating jaw members mounted to swing and means for swinging them outward toward and inward from the edges of said first mentioned jaw members, folding members parallel to said jaw members, and means for swinging them 25 about the outer edges of the jaw members and pressing means adapted to move toward and from said first mentioned jaw members, the swinging jaw members being timed to swing inward and the folding members being timed to swing outward and downward out of the path of said pressing means as they move toward the first mentioned jaw members.

12. In a machine for plaiting paper in the manufacture of paper boxes, jaw members for gripping the paper, a folding member swinging about said jaw members, pressing means and means for actuating said members and moving the folding member and one of the jaws out of the path of the pressing means and means for forcing the pressing member downward on the folded material to press the fold.

13. In a machine for plaiting paper in the manufacture of paper boxes, a pair of jaw members for gripping the paper, a folding member swinging about the jaw members, pressing means and means for actuating said members and moving the folding member and one of the jaw members out of the path of the pressing means and means for forcing the pressing member downward on the folded material to press the fold.

14. In a machine for plaiting paper in the manufacture of paper boxes, a jaw member, a coöperating jaw member mounted to swing and means for swinging it outward toward and inward from the edge of said first mentioned jaw member, a folding member parallel to said jaw members and means for swinging it about the outer edges of the jaw members and pressing means adapted to move toward and from the first mentioned jaw member, the swinging jaw member being timed to swing inward and the folding member being timed to swing outward and downward out of the path of the pressing means as it moves toward the first mentioned jaw member.

Signed by me at Baltimore, Md., this 12th day of February, 1914.

EDWARD D. SCHMITT.
